CLAIM

The ornamental design for a vent hood, as shown and described.

DESCRIPTION

FIG. 1 is a perspective view of a vent hood of the design;
 FIG. 2 is a front elevation view thereof;
 FIG. 3 is a back elevation view thereof;
 FIG. 4 is a right side elevation view thereof;
 FIG. 5 is a left side elevation view thereof;
 FIG. 6 is a top plan view thereof; and,
 FIG. 7 is a bottom plan view thereof.

The portions of the vent hood shown in broken lines form no part of the claimed design.

Diagonal shading is used to represent features that are transparent.

Dash-dot lines adjacent un-shaded areas represent bounds of the claimed design and form no part of the claimed design themselves.
